(57) **CLAIM**

The ornamental design for a clock face, as shown and described.

DESCRIPTION

FIG. 1 is a front perspective view of a clock face, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is an exploded front perspective view thereof.

The broken lines shown in the drawings depict portions of the clock face that form no part of the claimed design.
